UNITED STATES PATENT OFFICE.

FRANK W. MINICH, OF PORT WASHINGTON, NEW YORK.

ТИЛТИНГ-САШ WINDOW.

Application filed April 28, 1923. Serial No. 635,250.

My present invention relates to improvements in tilting sash windows, my object being to provide a window of this type which shall be thoroughly practical in all respects to build, install and operate, and which will have the hereinafter set forth other advantages.

In the drawings, which show the embodiment I at present prefer of my improvements, Fig. 1 is an elevational view of a tilting sash window construction within my invention as seen from the inside, i. e. as if from within the building, the two sash being shown shut or closed; Fig. 2 is the same except that the view is from the outside of the building; Fig. 3 is a vertical sectional view, partly in elevation, on a larger scale through the same, the building stone-work at the top and bottom of the window being also shown in vertical section, said figure being economized as to height at the two places indicated by the broken lines, and the sash being shown shut; Fig. 4 is a horizontal and sectional view, partly in plan, on the line 4—4 in Fig. 3, the stone-work of the building at the sides of the window being also shown in horizontal section, said drawing being economized as to width at the two places indicated by the broken lines; Fig. 5 is a view like Fig. 4 except that it is on the line 5—5 in Fig. 3, namely, is on a horizontal section through part of the lower sash and through one side only of the window frame; Fig. 6 is like part of the right side of Fig. 4 except that it shows certain removable panels detached; Fig. 7 is a vertical section, partly in elevation, on the line 7—7 in Fig. 4; Fig. 8 is like Fig. 3 except that the sash are both shown tilted inwardly into a horizontal position as for cleaning them; Figs. 9 and 10 are horizontal sectional views, partly in plan, respectively on the lines 9—9 and 10—10 in Fig. 8; Fig. 11 is a vertical sectional view, partly in elevation, on the line 11—11 in Fig. 4 looking in the direction of the arrows; Figs. 12 and 13 are broken away views in elevation of the aforesaid panels; Fig. 14 is a vertical sectional, partly elevational, view through one of the sash weight compartments on the line 14—14 in Fig. 11 looking in the direction of the arrows; Figs. 15 to 20 inclusive are views similar to Fig. 8 on a smaller scale, showing some further manipulations and relative positions of the sash possible with my construction.

I will now describe my improvements by

way of the particularly preferred embodiment thereof shown in the drawings but without limiting myself thereto except as may be required by the annexed claims 60 properly construed.

A, B and C designate respectively the top, bottom and sides of the stone or other building construction within which my window is shown mounted. 65

The drawings are intended to show a sheet metal fireproof construction of the sash, window frame, etc., but I do not limit myself to these materials.

1 and 2 respectively are the upper and 70 lower sash. The sides of the window frame severally comprise a sash weight compartment 3, together with a side section 4. These are united at the top by the headers 5 and at the bottom by the inner and outer 75 sills 6 and 7.

The side of each sash weight compartment 3 adjacent the sash is made up of three panels, 3^a, 3^b, 3^c (Figs. 3, 4, 6 and 11, etc.), the first being a fixed panel and the others 80 being detachable at will to get at the interior of the compartment. Said panels 3^b and 3^c are shown detached in Figs. 12 and 13. The panel 3^b is attached at the top by screws to a bracket 8 secured to the underside of the top of the sash weight compartment; and at the bottom is attached by screws to a cross piece 9 secured to the back of the panel 3^a as best shown in Figs. 3 and 11. Panel 3^c is attached by screws at the top 90 to a bracket 10 secured to the underside of the top of the sash weight compartment and at the bottom by screws to another bracket 11 secured to the bottom of said compartment (Figs. 3, 11 and 14). 95

Said panels 3^a, 3^b, 3^c are laterally spaced when in position and are shaped at their side edges to provide two guides located in each side of the window frame, namely, an inner guide 14 and an outer guide 15 (Figs. 100 8, 11 and 15 to 20 inclusive, etc.).

In the description and claims, the expressions "inner" and "outer" mean towards or nearer to respectively the interior and exterior of the building; and the same is true 105 of the expressions "inwardly" and "outwardly".

The outer guides 15 are straight up and down guides. The inner guides 14, for the greater part of their length, run parallel to 110 said outer guides except at the bottom where they incline downwardly and outwardly as

2 shown at 14^a (Fig. 11, etc.), and thence terminate each in a short vertical downwardly extending portion 14^b located directly under the adjacent outer guide 15, but without 5 communicating therewith.

The sash 1 and 2 have respectively pins at the top and bottom projecting from their sides, the bottom pins being designated 15 and the top pins 17, the latter being the free 10 ends of rods, designated by the same numeral, supported for free endwise movement in the upper rail of the sash, the inner ends of said rods being bent at right angles to project loosely into holes in a disk 18 (Figs. 15 4 and 7) fixed on the stem 19 rotatably supported in suitable bearings in said rail, said stem having an integral external head 20 on the inner side of the rail for operating said stem by partially rotating it and said disk to 20 simultaneously retract the projecting free ends of the rods 17 against the opposition of the springs 21 which normally impel them outwardly to the extent indicated in said Figs. 4 and 7 until stopped by the col- 25 lars 22 on said rods. The holes 23 in the ends of the head or handle 20 are adapted to be engaged by the hook on a window pole for retracting the aforesaid rods and pins 17, particularly of the upper sash which will 30 ordinarily be out of reach for direct manual operation.

The lower and permanent pins 16 of the upper sash 1 are always located in the outer guide 15; and similarly the corresponding 35 pins 16 of the lower sash 2 are always located in the inner guide 14. The lower halves of said guides are slots so that said lower pins 16 of both sash project through into the sash weight compartments 3 as best 40 shown in Figs. 5, 9, 10 and 11, where they each carry a metal piece 24 (Fig. 11) loosely rotatable thereon, to which latter in turn the sash cords or chains 25 are attached, said cords passing over pulleys 26 (Fig. 11) 45 suspended by links 27 from the top of the compartments 3, the other ends of said cords being attached to the sash weights 28 which, as usual, serve to counterbalance the weight of the respective sash.

50 The upper parts of the guides 14 and 15, being the parts shown shaded in Fig. 8, have bottoms bridging across between the sides of the guides so as to constitute grooves as shown at 14 in Fig. 4, as distinguished from 55 the slots 14 of Fig. 5. The lower portions of the guides must be slots in my construction in order that the sash weight cords can be fastened to the lower pins 16 of the sash, whereas the upper portions need not be slots 60 in my construction but can be grooves whose closed bottoms prevent one from seeing into the upper portion of the interior of the sash weight compartments.

To keep the sash weights separated and at 65 the same time avoid unnecessarily obstruct-

ing access to the interior parts of the sash weight compartments, I provide the partitions 30 (Fig. 4 etc.), one in each compartment, located substantially parallel to the plane of the window opening and projecting from one wall of the given compartment between the sash weights therein partially across to that wall of the compartment containing the guides for the sash.

The retractable upper pins 17 of the sash 1 may be located at will either in the outer guides 15 along with the lower pins 16 thereof which is the case when said sash has any of the positions of adjustment shown in Figs. 1, 2, 3, 4, 11, 15, 16, 17 or 20; or said 75 retractable upper pins of said sash 1 may be adjusted into the other or inner guides 14 as in Fig. 18; or they may be located in neither guide and merely allowed to bear against the adjacent faces of the sash weight compartments 3 as in Fig. 19, and in this instance the projecting beads 29 (Figs. 4 and 19 etc.) are specially provided for the purpose of forming lateral stops for the pins 17, preventing the sash from unintentionally or accidentally tilting and falling 80 downwardly to a greater angle to the vertical than that shown in said Fig. 19.

90 Next, referring to the other sash 2, this also can be adjusted into numerous positions depending upon whether its retractable upper pins 17 are adjusted into or out of the guides 14 and 15, and also dependent upon whether the lower pins 16 of said sash are located in the straight upper portion of the inner guides 14, or are in the inclined portions 14^a, or the lower vertical portion 14^b thereof, some of said possible different 95 adjustments of said sash 2 being shown in Figs. 3, 15, 16, 17, 20, etc.

100 Fig. 15 shows both sash in their shut position, from which it will be seen that both are located in the same plane. In this instance, all of the pins of the sash 1 are in the outer guides 15 as are also the upper pins 17 of sash 2, but the lower pins 16 of the latter sash are located in the vertical bottom ends 14^b of the other or inner guides 14. In this position it is impossible to raise or lower either sash, nor can either sash be 105 tilted inwardly from the outside of the building. Of course, from the inside, the handles 20 can be operated to retract the upper pins 17 of either or both sash to permit them to be tilted, raised and lowered as 110 desired.

115 Fig. 8 shows still another adjustment of the sash for cleaning their outer or weather faces from within the room, wherein the sash 2, after retracting its upper pins 17, has been tilted inwardly and downwardly 120 so that its outer face can be cleaned, whereupon the upper sash 1 can be lowered in the guides 15 and then, after retracting its upper pins 17, can also be tilted inwardly and 125 130

downwardly into the position shown in Fig. 8 to have its weather face cleaned.

When in this position, the sash weights would pull up the outer ends of the sash were it not that I provide to prevent this, short lateral branches 14^c and 15^c (Figs. 8, 11 and 20) extending upwardly and outwardly respectively from the vertical lower portions of the guides 14 and 15 adjacent to the bottom thereof, into which the sash weights quite naturally pull the lower pins 16 of the sash when they are in the act of being tilted down as in Fig. 8, whereupon said ends of the sash are prevented from being lifted by the sash weights.

When the sash are shut, as in Figs. 3 and 15, I provide means first, to keep out the weather at the horizontal joint or space between the two sash; second, at the space 20 between the bottom of the lower sash and the outer sill; and third, at the sides of both sash between same and the sides of the window frame.

Describing these in the order named, I provide a wide extension 32, of substantially the same width as the sash, from the bottom rail of the upper sash 1, said extension having an inwardly turned lower edge 32^a (Figs. 3 and 8), the latter being receivable 30 into a longitudinally extending groove 33 (Fig. 8) in the outer face of the top rail of the lower sash when both are shut.

Also, I provide a similar wide extension 34 (Figs. 3 and 8) from the bottom rail of the lower sash 2 with an inwardly turned lower edge 34^a, the latter being receivable into a longitudinal groove 35 (Fig. 8) in the outer sill when said sash is shut.

To keep the window weather-tight at the sides, I provide strips 36 (Figs. 3, 8, 9 and 10 etc.) projecting from the weather face of each sash along the side edges thereof, receivable, when the sash are shut, into elongated groove-like inwardly opening but outwardly closed recesses in vertical members 38 secured to the sides of the window frame.

In short, I have provided by my improvements a thoroughly practical tilting-sash window-construction, some of the advantages of which are the following:

(1) Sightly appearance when the sash are shut due to their being in the same plane.

(2) The sash when shut cannot be opened from the outside, this feature being contributed to by the fact that the lower pins of the lower sash, when shut, are located in the short vertical guides 14^b.

(3) Either or both sash can be adjusted for ventilation, etc., to a great variety of 60 positions as desired to suit conditions.

(4) The weather faces of the sash can be cleaned from within the room.

(5) The sash when closed make a weather-tight window all around, sides, bottom 65 and top.

(6) The construction of the sash weight compartments with their removable panels permits of ready access to the working parts within said compartments. 70

What I claim is:

1. In a multiple tilting-sash window-construction, the combination of a plurality of sash having respectively pins at the top and bottom projecting from their sides, the top pins being retractable at will; and a window frame whose sides are each provided with adjacent inner and outer vertically extending guides for the pins of said sash, the lower part of each inner guide inclining 80 downwardly and outwardly and terminating under the lower end of the adjacent outer guide but without communicating therewith. 85

2. In a multiple tilting-sash window-construction, the combination of a plurality of sash having respectively pins at the top and bottom projecting from their sides, the top pins being retractable at will; and a window frame whose sides are each provided 90 with adjacent inner and outer vertically extending guides for the pins of said sash, the lower part of each inner guide inclining downwardly and outwardly and terminating in a short vertical portion extending 95 downwardly from said inclined part under the lower end of the adjacent outer guide but without communicating therewith.

3. In a multiple tilting-sash window-construction, the combination of a plurality of sash having respectively pins at the top and bottom projecting from their sides, the top pins being retractable at will; a window frame whose sides are each provided with adjacent inner and outer vertically extending guides for the pins of said sash; a vertically extending projecting bead on the side of the window frame at its front edge independent of said guides adapted to be engaged by the top pins of the sash to prevent 100 unintentional excessive down-tilting thereof. 105

Signed at Boston in the county of Suffolk and State of Massachusetts this 24th day of April A. D. 1923.

FRANK W. MINICH.
